UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR USE IN DECOMPOSING METALLIC SALTS AND DESULPHURIZING ORES.

SPECIFICATION forming part of Letters Patent No. 399,122, dated March 5, 1889.

Application filed January 3, 1889. Serial No. 295,368. (No model.)

To all whom it may concern:

Be it known that we, PHINEAS H. ADAMS, Jr., and ORSEMAS T. X. ADAMS, citizens of the United States, residing at Chicago, Illinois, have invented certain new and useful Improvements in Apparatus for use in Decomposing Metallic Salts and Desulphurizing Ores, of which the following is a specification.

The object of our invention is to improve an apparatus for mechanically decomposing chemical compounds, metallic salts, and desulphurizing ores or their resulting material, when the substances treated are in a molten condition, by the action of centrifugal force; and our invention consists in the features and details of construction hereinafter described and claimed.

In the drawings, Figure 1 is a vertical longitudinal section of our apparatus with the running-gear in elevation. Fig. 2 is a transverse vertical section taken in the line 2 2 of Fig. 1, showing the arrangement of the actuating-shaft and the means employed to prevent friction, looking in the direction of the arrow. Fig. 3 is a plan view of the bottom or end of the receiving-vessel. Fig. 4 is an elevation showing the entrance-pipe, looking out from the interior of the receiving-vessel; and Fig. 5 shows the receiving-vessel somewhat modified in form.

In making our improved apparatus for decomposing chemical compounds, metallic salts or salts of metal, and desulphurizing ores, we make a vessel, V, constructed and adapted to receive the substance to be treated when in a molten condition. This receiving-vessel may be made in such a way as will secure the required strength and reduce the conduction of heat from the interior to the exterior. It may be surrounded by curbing and have a removable bottom or end to facilitate the removal of the material which is not thrown off at the mouth by the action of centrifugal force; and in other respects it may be made as will be calculated to subserve the end in view and permit of its being rotated at a high rate of speed for the separation of particles of different degrees of density in the matter treated. Many of these parts and the details of their construction, as they do not form the special subject-matter of our present claims, need not

be more fully described, as they will be sufficiently understood from an inspection of the drawings. The receiving-vessel, however, is intended to be rotated in a horizontal instead of a vertical position, and therefore necessitates a special adaptation of various parts to this end, as hereinafter described.

An actuating-shaft, A, is arranged in horizontal journals or bearings supported in a suitable frame-work, which may be indicated by the letter B. This frame-work will of course be of a size and strength adequate to sustain the heavy weight of the receiving-vessel with its load of molten material. One of the journals, C, may be a plain bearing or box, in which the outer end of the actuating-shaft rests and revolves. The other bearing, D, however, we prefer to make as shown in Fig. 2, where it consists of a box adapted to receive a number of rollers or wheels, E, preferably journaled in suitable bearings in the sides of the box and affording just sufficient space in the center for the passage of the actuating-shaft, so that its surface will bear against the surface of the wheels or rollers E. By this arrangement extreme or injurious friction will be prevented between the actuating-shaft and the bearings as it operates under the heavy load or strain to which it will be subjected, as hereinafter described.

The pulley or belt surface F is connected to any convenient source of power, so as to rotate the actuating-shaft and the receiving-vessel to which it is attached. The inner end of the actuating-shaft is provided with a collar, G, which has flanges H. (Shown in section in Fig. 1.) This collar, with its flanges, is keyed or otherwise fixed to the actuating-shaft, so that it will rotate as it revolves. The flanges H are connected to the bottom or end of the receiving-vessel in such a way as to carry the receiving-vessel around with their revolutions. We prefer to form this connection in a way that will permit some yielding or flexibility between the parts, and to that end we prefer to connect the flanges H to the end or bottom of the receiving-vessel by a number of bolts, I, with some space between the flanges and the bottom of the receiving-vessel, and to surround the bolts I with coiled springs of sufficient strength to hold

the parts apart from each other to the extent allowed by the bolts. At the same time the presence of these springs will permit sufficient play to accommodate any vibration that might 5 occur in the receiving-vessel while being rotated at a high rate of speed, and at the same time permit the actuating-shaft to be rigidly held in a horizontal position without being sensibly affected by the vibrations of the receiving-vessel.

10 We have thus described and illustrated a manner of attaching the receiving-vessel to the actuating-shaft to permit of sufficient flexibility to accommodate the parts to the vibrations of the receiving-vessel in operation; but as other means can obviously be used to secure a flexible or yieldable connection, we do not desire to unnecessarily limit ourselves to details of construction in this particular.

15 The receiving-vessel, as before said, is intended to be arranged in a horizontal position. Its mouth is made sufficiently open to permit a constant inflow of molten material to be treated, while at the same time it serves for 20 the discharge of the material which is thrown off by the action of centrifugal force. To permit this we prefer to introduce the molten material through a pipe or spout, J, which enters the mouth of the receiving-vessel at a 25 slightly-downward inclination and carries the material to be treated almost to the bottom or farther end of the vessel. This pipe or spout leaves sufficient space around it to permit the passage of the molten material thrown off by the action of centrifugal force; and to 30 retain the heat in the receiving-vessel we prefer to arrange a plate or cover, X, before its mouth, provided with a suitable hole for the admission of the pipe or spout. This cover may 35 be made adjustable toward and from the mouth of the receiving-vessel, if desired, to regulate the space between them. To catch the material as it is thrown off we prefer to 40 arrange a chamber, K, into which the mouth 45 of the receiving-vessel opens. This chamber is surrounded by a curbing or other means to catch the molten material as it is thrown off, and means may be employed, as a pipe, L, to 50 discharge streams or jets of water onto such material in order to prevent overheating. A spout is arranged at the bottom of this chamber, through which the molten material thrown off may pass to a car, M, or other receptacle adapted to receive and remove it.

55 To heat the interior of the receiving-vessel,

or to prevent it from cooling during an interruption of its operation, or for other purpose, we also prefer to provide a furnace, N, by means of which a blast of air, driven by a blast-fan or other means, may be heated and 60 discharged into the receiving-vessel, as shown in Fig. 1.

In Fig. 5 we have shown the receiving-vessel as enlarged and separable at the mouth end, instead of at the other end, as shown in 65 Fig. 1. This modification is for the purpose of facilitating the removal of that portion of the material treated which is not thrown off by the action of centrifugal force, if it be preferred to remove at that instead of at the 70 other end of the receiving-vessel.

What we regard as new, and desire to secure by Letters Patent, is—

1. In an apparatus for decomposing metallic salts or salts of metals and desulphurizing 75 ores when in a molten state, the combination of a horizontal revoluble receiving-vessel adapted to receive molten material to be treated, a horizontal revoluble actuating-shaft rotating said vessel as it revolves, a pipe or spout 80 entering the receiving-vessel through its mouth and discharging the molten material to be treated into the receiving-vessel at or near its farther end, means for supplying heat to the interior of the receiving-vessel, and 85 means for rotating the actuating-shaft, substantially as described.

2. In an apparatus for decomposing metallic salts or salts of metals and desulphurizing 90 ores when in a molten state, the combination of a horizontal revoluble receiving-vessel adapted to receive molten material to be treated, a horizontal revoluble actuating-shaft rotating said vessel as it revolves, a pipe or spout 95 entering the receiving-vessel through its mouth and discharging the molten material to be treated into the receiving-vessel at or near its farther end, a plate or cover before the mouth of the receiving-vessel, with space 100 between the plate or cover and the mouth of the receiving-vessel for the discharge of the molten material thrown off by the action of centrifugal force, and means for rotating the actuating-shaft, substantially as described.
